DESIGN FOR A COMBINATION MIRROR AND MEMORANDUM TABLET OR SIMILAR ARTICLE

Joseph H. Fox, Long Island City, N. Y.

Application April 3, 1936, Serial No. 61,926

Term of patent 3½ years

To all whom it may concern:—

Be it known that I, Joseph H. Fox, a citizen of the United States, residing at Long Island City, in the county of Queens and State of New York, have invented a new, original, and ornamental Design for a Combination Mirror and Memorandum Tablet or Similar Article, of which the following is a specification, reference being had to the accompanying drawing, forming part thereof.

Fig. 1 is a front elevational view of a combination mirror and memorandum tablet or similar articles showing my new design; and

Fig. 2 is an edge view thereof.

The design is characterized by a double faced mirror, one face being plain and the other face provided with an area of frosted surface finish extending from the bottom to a point near the top thereof, and lines of similar frosted finish arranged parallel to the sides of the main area, such lines being positioned on one side and at the top of the main frosted area and appreciably spaced therefrom.

I claim:

The ornamental design for a combination mirror and memorandum tablet or similar article, substantially as shown and described.

JOSEPH H. FOX.
